UNITED STATES PATENT OFFICE.

TONJES A. BOTH, OF STRATFORD, CONNECTICUT, ASSIGNOR TO THE CONNECTICUT ELECTRIC MANUFACTURING COMPANY, OF BRIDGEPORT, CONNECTICUT, A CORPORATION OF CONNECTICUT.

DESIGN FOR A FACEPLATE FOR ELECTRICAL WALL DEVICES.

Application filed December 19, 1924. Serial No. 11,746. Term of patent 14 years.

To all whom it may concern:

Be it known that I, TONJES A. BOTH, a citizen of the United States, residing at Stratford, county of Fairfield, State of Connecticut, have invented a new, original, and ornamental Design for a Faceplate for Electrical Wall Devices, of which the following is a specification, reference being had to the accompanying drawing, forming part thereof.

Fig. 1 is a front elevation of a face plate

for electrical wall devices embodying my new design, and

Fig. 2 is a side or edge elevation thereof. The stippled portion in the drawing represents a dull finish contrasting with the plain polished surface.

I claim:

The ornamental design for a face plate for electrical wall devices substantially as shown and described.

TONJES A. BOTH.
